UNITED STATES PATENT OFFICE.

WEBB JAY, OF CHICAGO, ILLINOIS.

VACUUM FUEL-FEED DEVICE.

1,308,848.

Specification of Letters Patent.

Patented July 8, 1919.

Continuation in part of application Serial No. 206,506, filed December 10, 1917. This application filed October 7, 1918. Serial No. 257,248.

To all whom it may concern:

Be it known that I, WEBB JAY, a citizen of the United States, residing at Chicago, in the county of Cook and the State of Illinois, have invented certain new and useful Improvements in Vacuum Fuel-Feed Devices, of which the following is a specification, reference being had to the accompanying drawings, forming a part thereof.

10 This application is a continuation in part of my application, Serial No. 206,506, filed December 10th, 1917, and allowed February 16th, 1918. The purpose of the invention herein presented is to provide an improved 15 and simplified device for the purposes to which the so-called vacuum feed is commonly applied in supplying fuel from a low level tank to a supplemental tank at a higher level for feeding a carburetor. It consists 20 in the elements and features of construction and their combinations hereinafter described and shown in the drawings, as indicated by the claims.

In the drawings:

25 Figure 1 is a vertical sectional view showing the low level tank and the supplemental higher tank of the vacuum fuel feed system embodying this invention.

Fig. 2 is a detail section taken as indicated at line, 2—2, in Fig. 1.

Fig. 3 is a detail section similar to Fig. 2, illustrating a modification.

Fig. 4 is a detail section taken as indicated at line, 4—4, on Fig. 3.

35 In the drawings the low level main supply tank is shown at A, and the supplemental elevated feed tank is shown at B. Said feed tank, B, has the usual vacuum chamber, 1, which has a suction connection by the pipe, 2, leading from any suitable source of suction, usually the intake manifold of the engine to be served. 3 is a fuel supply pipe leading from the lower part of the main low level tank, A, and discharging into the upper part of the vacuum chamber, 1, of the elevated feed tank, B. From said vacuum chamber, 1, the liquid fuel is discharged into a reserve chamber or reservoir, 4, as usual, past a check valve, 5, which is opened by the 45 gravity flow of the liquid fuel and is held seated by suction when there is partial vacuum operative in the vacuum chamber, 1.

So far as above described, the construction is common and familiar.

In the main low level tank, A, there is 55 provided, preferably at the upper part thereof, a chamber which is herein referred to as a timing chamber for the reason that its capacity relatively to that of a certain conduit through which it is emptied serves as 60 a measure for the time or period of the successive operations of filling the vacuum chamber, 1, with the liquid fuel derived from the main low tank, A. This timing chamber, 6, is in communication with the 65 liquid fuel conduit, 3, which for this purpose may conveniently extend down alongside said timing chamber as shown in the drawings, having a lateral spout and port for discharge into said timing chamber, 70 shown at 7, and controlled by a check valve, 8, which is opened by gravity flow from the conduit, 3, into the timing chamber, and is adapted to be held seated by suction operating in said conduit, 3. It may be understood that the main low tank, A, and the timing chamber are constantly open to atmospheric pressure, as indicated by the air vent orifices, 9, 10, and 20.

For supplying fuel to the vacuum chamber, 1, there is provided in addition to the conduit, 3, a relatively restricted conduit, 12, leading from the lower part of the timing chamber, 6, and discharging into the top of the vacuum chamber, 1; and an additional 80 function of said restricted conduit, 12, is to supply atmospheric pressure to the vacuum chamber, 1, after a predetermined quantity of liquid has been sucked out of the timing chamber, 6, through said conduit, 12, leaving the lower end of the conduit unsealed and open to the atmosphere in the timing chamber. Preferably the suction pipe, 2, communicates with the vacuum chamber, 1, through a comparatively small aperture, 85 having a capacity closely comparable with that of the restricted conduit, 12, because, as shown, the device is designed to operate with continuous suction and without a suction-controlling valve.

To insure the initial sealing of the lower end of the pipe, 12, the filling nipple for the tank, A, is preferably made as shown at 90 13, leading directly into the timing chamber, 100

ber, and said timing chamber overflows into the main tank through the overflow port, 14; thus whenever the tank, A, is filled, the timing chamber, 6, will first be filled up to 5 the level of the overflow port, 14, so that as soon as suction is applied to the vacuum chamber, 1, through the pipe, 2, a partial vacuum will be created therein, and a flow of liquid from the main tank, A, through 10 the pipe, 3, will be started. It may be noticed that the timing chamber, 6, is provided with a false bottom or baffle, 16, but said false bottom is apertured at 17, for communication with the space below into 15 which space the pipe, 12, opens for access to the liquid in the timing chamber or to the air in said chamber when the liquid has been exhausted.

The operation of the structure described 20 is as follows: Assuming that the main tank, A, has been supplied with liquid fuel and that a supply of liquid is present in the timing chamber, sealing the lower end of the pipe, 12, it will be evident that suction 25 operative through the pipe, 2, will produce a partial vacuum in the chamber, 1, and liquid will be drawn through the conduit, 3, from the main tank, A, and discharged into said vacuum chamber while the timing 30 chamber, 6, is simultaneously exhausted by suction through the pipe, 12, until the lower end of said pipe no longer dips into the liquid in the timing chamber but is open to atmosphere therein. When this condition is 35 reached, the air supplied to the chamber, 1, through the pipe, 12, being sufficient to satisfy the suction from pipe, 2, will dissipate the partial vacuum in the chamber, 1; in other words, atmospheric pressure will be 40 come dominant for the time being, and the check valve, 5, being no longer held to its seat by the suction will open and permit the contents of the vacuum chamber, 1, to be emptied into the reservoir, 4. At the same 45 time, however, the discharge mouth of the pipe, 3, in chamber, 1, being submerged for some distance in the liquid, a portion of said liquid will be siphoned back through the pipe, 3, and emptied into the timing chamber, 6, through the port, 7, by gravity opening 50 of the valve, 8, said valve being light enough to be opened by a very slight pressure from the column of liquid in the pipe, 3; furthermore, to insure such discharge of 55 the liquid through the port, 7, rather than back into the tank, A, there may be provided at the foot of the pipe, 3, an outwardly-seating check valve, 3^a. Thus while the main body of the liquid in the chamber, 1, is being 60 transferred by gravity into the chamber, 4, a small quantity of said liquid is siphoned back to the timing chamber for again sealing the lower end of the pipe, 12, to permit refilling of the vacuum chamber, 1, by renewed dominance of suction therein. 65

Though the port, 7, is of ample dimensions to permit a quick or sudden deluging of the timing chamber, so that an adequate quantity of liquid will be furnished thereto before the level in the chamber, 1, falls below 70 the discharge mouth of pipe, 3, therein, the false bottom, 16, and relatively restricted aperture, 17, therein, will delay the accumulation of liquid on the true bottom of the chamber, 6, and thus delay the sealing of the 75 pipe, 12, long enough to permit the complete evacuation of the chamber, 1, through the valve, 5. If desired any other or additional baffling means beside the apertured false bottom, 16, may be employed for further delaying the arrival and accumulation 80 of liquid in the lower space of the timing chamber, 6. Figs. 1 and 2 illustrate baffles, 18, upstanding from the bottom of the timing chamber, each stopping short of the 85 same at one end, and alternate baffles so stopping short at opposite ends, thus forming a tortuous lane which the liquid must traverse from the aperture, 17, in the false bottom, 16, before it reaches the intake end 90 of the air pipe, 12.

Another expedient for increasing the delay in the sealing of the air vent pipe, 12, consists in providing a small leak port, 19, formed in said pipe, 12, at a distance above 95 its lower end, but still within the chamber containing the baffles, 18, so that the suction acting on the pipe, 12, will continue to be practically satisfied through said vent, 19, even after the liquid has risen above the lower end of the pipe, and until the liquid level actually covers said vent, 19. Then the flow of liquid being established through the pipe, 12, to the vacuum chamber, 1, the air vent will be effectually sealed, and said flow 100 having once been established will continue, even after the level of the liquid has fallen below the vent, 19, and until said level actually drops below the intake end of the pipe, 12. 105

An alternate form of baffle, 21, is illustrated in Figs. 3 and 4, in which each of the baffles extends entirely across the space below the false bottom, 16, that is, from side to side thereof, but not upwardly quite to the said bottom, 16. Each baffle, 21, thus constitutes a dam, and the liquid coming through the restricted aperture, 17, must accumulate and successively overflow the several dams, 21, in order to reach the intake 110 end of the pipe, 12. However, to insure the withdrawal from between the dams of practically the entire quantity of liquid accumulated, there are provided small drain apertures, 22, near the bottom of each dam, as 115 seen in Figs. 3 and 4. The relative capacities of the aperture, 17, drains, 22, and the pipe, 12, will be such that when once the flow of liquid has been reestablished through 120 the pipe, 12, it can be maintained through 125 the pipe, 12, it can be maintained through 130

the drains, 22, and that an adequate flow through said drains will in turn be maintained from the aperture, 17, until the space above the false bottom, 16, has been entirely exhausted. That is, the capacity of the aperture, 17, should be slightly greater than that of either aperture, 22, and the capacity of each aperture, 22, (since either one may have to act alone if the tank is tilted) should be slightly greater than that of pipe, 12.

While it is important to provide for a sufficient time interval between the discharge of liquid through the port, 7, into the timing chamber, and the final sealing of the pipe, 12, by said liquid in the chamber, it is still more important to accurately adjust the time required for withdrawing from the timing chamber the liquid accumulated therein, and thus measuring the period through which the suction is permitted to act on the vacuum chamber for filling it with liquid through the pipe, 3. In other words, the time required for transferring a given quantity of liquid from the timing chamber through the pipe, 12, should equal the time required for transferring from the main tank, A, to the vacuum chamber, 1, a quantity sufficient to nearly fill said chamber and submerge the discharge end of the pipe, 3, sufficiently for re-filling the timing chamber, 6, by the siphon action when atmospheric pressure is permitted to dominate the suction in the vacuum chamber. For originally adjusting the rate of flow of liquid through the pipe, 12, to accomplish this result, a choker, 11, is provided at any conveniently accessible point in the pipe, 12, so as to be adjustable for choking the pipe to exactly the desired extent when the device is originally installed, the proper degree of choking being somewhat dependent upon the directness of the pipe, 12, and its length which will vary in different installations.

45 I claim:—

1. A vacuum fuel feed system of the kind in which the fuel is supplied from a main low level supply tank through a liquid fuel conduit, extending from the lower part of said tank, to an elevated supplemental feed tank provided with a vacuum chamber having a suction connection, characterized by a timing chamber open to the atmosphere disassociated from the supplemental tank except as hereinafter specified, provided with means for supplying liquid by gravity to said timing chamber and preventing back-flow therefrom through said means and having an air conduit from the lowest part of the timing chamber to the upper part of the vacuum chamber adapted to admit air from the timing chamber into the vacuum chamber when the liquid level in said timing chamber is below the intake of said air conduit.

2. A vacuum fuel feed system of the type claimed in claim 1 wherein the means for supplying the timing chamber consists of an outflow connection from the liquid conduit which extends from the main low level supply tank to the elevated supplemental feed tank, and the means for preventing back-flow being a check valve adapted to be held seated by suction operative in said liquid conduit.

70

3. A vacuum fuel feed system of the type claimed in claim 1 having means for variably restricting the air conduit.

75

4. A vacuum fuel feed system of the type claimed in claim 1, wherein the liquid fuel conduit which extends from the main low level supply tank into the vacuum chamber of the elevated supplemental feed tank has its opening for discharge into said vacuum chamber at a distance below the top thereof, whereby the liquid to the capacity of the vacuum chamber above said discharge opening may be siphoned back into the timing chamber.

80

5. In a vacuum fuel feed system, a chamber for timing the evacuation and filling operation, means for supplying and conducting liquid to said chamber by gravity flow; an air vent pipe leading from the lower part of said chamber adapted to be sealed by the liquid supplied by said means, and means in said chamber for delaying the advance of the liquid from its delivery into said chamber to its arrival at the intake mouth of said air vent pipe of the liquid supplied by gravity flow to the timing chamber.

85

6. A vacuum fuel feed system of the type claimed in claim 5, wherein the delaying means comprises a partition in the timing chamber between the liquid entrance thereto and the intake of the air conduit, said partition having a restricted aperture for the passage of liquid therethrough.

90

7. A vacuum fuel feed system of the type claimed in claim 5, wherein the delaying means comprises a false bottom in the timing chamber having a restricted aperture for the passage of liquid therethrough, the space below the false bottom having communication with atmospheric pressure independently of the restricted liquid aperture through said false bottom.

95

8. In a construction as defined in claim 5, the delaying means comprising a false bottom in the timing chamber and baffling partitions up-standing from the true bottom partitioning the space between the same and the false bottom to form a tortuous passage through said space to the intake of said air vent pipe.

105

9. A vacuum fuel feed system of the type claimed in claim 1, wherein the means for supplying the timing chamber consists of an outflow connection from the liquid conduit which extends from the main low level

110

115

120

125

130

supply tank to the elevated supplemental feed tank, and the means for preventing backflow is a check valve which is adapted to be held seated by suction operative in 5 said liquid conduit, said conduit being provided with a check valve seating against backflow into said low level tank and posi-

tioned below the outflow connection from said conduit in the timing chamber.

In testimony whereof, I have hereunto set 10 my hand at Chicago, Illinois, this 27th day of September, 1918.

WEBB JAY.
